Clare E. Hodgman, Mamaroneck, N. Y.

Application May 4, 1954, Serial No. 30,328

Term of patent 14 years

(Cl. D61—1)

FIG. 4.

FIG. 1.

FIG. 2.

FIG. 3.

Fig. 1 is a perspective view of the front and one side of a photographic camera in an operating position, showing my new design;

Fig. 2 is a front elevational view thereof in a non-operating position; and

Fig. 3 is a rear elevational view.

Fig. 4 is a top view thereof in operating position.

The side of the camera not shown is substantially plain.

The dominant feature of my design resides in the portions shown in full lines.

I claim:

The ornamental design for a photographic camera, substantially as shown and described.
